Primary Examiner — Celia Murphy*Assistant Examiner* — Clare Ann Gannon(74) Attorney, Agent, or Firm — Drinker Biddle & Reath LLP(57) CLAIM

The ornamental design for a therapy mat, as shown and described.

DESCRIPTION

FIG. 1 is a perspective view of the therapy mat showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines illustrate features that form no part of the claimed design.

1 Claim, 4 Drawing Sheets(56)
